UNITED STATES PATENT OFFICE.

JOHN GUEDEL, OF CANAL DOVER, OHIO.

SCREW-THREAD-CUTTING TOOL.

SPECIFICATION forming part of Letters Patent No. 326,733, dated September 22, 1885.

Application filed May 21, 1885. (No model.)

To all whom it may concern:

Be it known that I, JOHN GUEDEL, a citizen of the United States, residing at Canal Dover, in the county of Tuscarawas and State of Ohio, have invented a new and useful Improvement in Screw-Thread-Cutting Tools, of which the following is a specification, reference being had to the accompanying drawings.

My invention relates to improvements in screw-thread cutters; and it consists in the improved construction and combinations of devices that will be more fully described hereinafter, and particularly pointed out in the claims.

15 In the drawings, Figure 1 is a side elevation. Fig. 2 is a view taken at right angles to Fig. 1. Figs. 3 and 4 are detail views.

A represents a spindle or shank, which has one end reduced, as at D, and adapted to fit in an ordinary bit-stock, and is provided with a screw-thread, C, which extends for a suitable distance along the spindle. Formed with the spindle, at one end thereof, is a rigid jaw, D', and to this spindle, at the point E, is pivoted 25 a jaw, F. A spring, G, bears between the jaws and serves to keep them normally open.

H I represent thumb-nuts, which work on the threaded portion of the spindle, and in between these thumb-nuts on the spindle slides a collar, 30 K, which is provided with lugs L on opposite sides. To these lugs are fulcrumed hand-levers M. The forward ends of the jaws D' and F are formed into enlarged heads, as shown, and from these heads to the reduced portions 35 of the jaws are inclines N.

O represents a collar, which is beveled on its inner side and adapted to fit the inclines N, and is provided on its rear side with rearwardly-extending lugs P, to which are fulcrumed 40 levers R, which are also connected to the levers M. It will be seen by this construction that the levers M and R form toggles, which are adapted to move the ring O back and forth upon the inclines N by opening or closing the 45 levers M, and thereby cause the pivoted jaw F to approach or recede from the rigid jaw D'. In the ends of the heads of the jaws are cut dovetailed mortises or grooves S, in the faces of which are made rectangular recessed 50 grooves T.

U represents dies for cutting threads, which are inserted into the dovetailed mortises, and

are provided on their under sides with ribs V, which enter the grooves T. Set-screws W bear against the dies and secure them firmly in place, and allow them to be readily removed from the heads when desired. Set-screws X extend through the heads at right angles to the screws W, and the inner ends of the screws X are adapted to bear against the opposing 55 faces or inner sides of the jaws. These screws X serve to regulate the play of the jaws and prevent them from coming too close together. The dies U are removable, so that they may be replaced by others adapted for cutting 60 coarser or finer threads upon bolts of different diameters.

The operation of my invention is as follows: After the dies have been secured in the heads the set-screws X are adjusted so as to enable 70 the jaws to come together to the required extent, and the collar K is moved on the spindle by turning the thumb-nuts H and I far enough to cause the collar O to clamp the dies together upon the bolt or rod upon which the thread is 75 being cut by opening the outer ends of the levers M. By inserting the end B in a bit-stock a rotary motion can be imparted to the thread-cutter, as will be very readily understood, and thereby cause it to readily cut the 80 threads. The screws W not only enable the dies to be removed from the heads of the jaws, but also enable them to be adjusted closer together in order to compensate for wear on the die, and thus permit the latter to be recut after 85 having become dull or worn, and thus enable the dies to be used for a very great length of time.

Having thus described my invention, I claim--

1. The combination of a rigid jaw and a pivoted jaw having the dovetailed mortises in their enlarged heads with the thread-cutting dies U, inserted in the mortises, the set-screws for clamping the dies in the mortises, the set-screws X, for regulating the movement of the jaws, and means for clamping the jaws together, substantially as described.

2. The combination of the spindle having the rigid jaw and the pivoted jaw, the thread-cutting dies secured in the heads of the jaws, said jaws being provided with the incline N, the levers M, fulcrumed to the spindle, the collar O, working on the inclines N, and the

levers R, connecting the collar O with the levers M, substantially as described.

3. The combination of the threaded spindle C, having the rigid head or jaw and the pivoted jaw, said jaws being provided with the inclines N, the thread cutting dies adapted to be secured in the heads of the jaws, the thumb-nuts H and I on the threaded spindle, the sliding collar K on the spindle between the nuts H and I, the levers M, fulcrumed to the collar K, the collar O, working on the inclines N, and the levers R, connecting the collar O with the levers M, substantially as described.

4. The combination, with the pivoted jaw and the rigid jaw having the dovetailed grooves S, provided with recesses T, of the thread-cutting dies U, having the ribs V engaging with recesses T, and set-screws for clamping the dies in place, substantially as described. 15

In testimony that I claim the foregoing as 20 my own I have hereto affixed my signature in presence of two witnesses.

JOHN GUEDEL.
